US0D1025981S

(12) **United States Design Patent** (10) **Patent No.:** **US D1,025,981 S**
(45) **Date of Patent:** **** May 7, 2024**

(54) **INFORMATION HANDLING DEVICE**

(71) Applicant: **Dell Products L.P.**, Round Rock, TX (US)

(72) Inventor: **Duck Soo Choi**, Austin, TX (US)

(73) Assignee: **Dell Products L.P.**, Round Rock, TX (US)

(**) Term: **15 Years**

(21) Appl. No.: **29/754,901**

(22) Filed: **Oct. 15, 2020**

(51) **LOC (14) Cl.** **14-02**

(52) **U.S. Cl.**

USPC **D14/315**

(58) **Field of Classification Search**

USPC ..... D14/127, 138 AB, 214, 217, 299, 300, D14/315, 322, 326, 327, 331, 334, 341, D14/345, 348, 432, 439, 496, 507;

D18/12.3

(57) **CLAIM**

The ornamental design for an information handling device, as shown and described.

DESCRIPTION

FIG. 1 is a front perspective view of the information handling device, showing my new design;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a rear perspective view thereof;

FIG. 9 is a front perspective view thereof, showing the information handling device in an opened state; and, FIG. 10 is another rear perspective view thereof, showing the information handling device in an opened state.

The broken lines shown in the drawings illustrate portions of the information handling device and form no part of the claimed design.

1 Claim, 7 Drawing Sheets
